ICE SIGN

Filed May 27, 1930

William H. Sandefur,
INVENTOR

BY *Victor J. Evans*

Levi St. Amis,
WITNESS:

WITNESS:

UNITED STATES PATENT OFFICE

WILLIAM HENRY SANDEFUR, OF FORT VALLEY, GEORGIA

ICE SIGN

Application filed May 27, 1930. Serial No. 456,267.

This invention relates to signs and more particularly to a sign which may be displayed for the purpose of indicating to an ice-man, the quantity of ice to be left at the house, upon a door or door frame of which, for example, the device may be suspended, and the primary object of the invention is to provide a device for this purpose in which ordinal-bearing plates may be dismountably suspended upon the face of a main plate so as to give a total of the number of pounds of ice to be delivered.

Another object of the invention is to provide, in combination with the means for suspending the ordinal-bearing plates, referred to above, means for confining the lower edges of the plates so as to prevent the plates being blown loose from the suspension means.

Another object of the invention is to provide, in connection with the main plate of the device, a pocket in which a plurality of groups of the ordinal-bearing plates may be arranged and maintained in separate positions.

This invention also consists in certain other features of construction and in the combination and arrangement of the several parts to be hereinafter fully described, illustrated in the accompanying drawing and specifically pointed out in the appended claims, it being understood of course that minor changes may be made so long as they fall within the scope of the claims.

In describing my invention in detail, reference will be had to the accompanying drawing, wherein like characters denote like or corresponding parts throughout the several views, and in which:

Figure 1 is a view in front elevation of the device embodying the invention.

Figure 2 is a vertical front to rear sectional view taken on the line 2—2 of Figure 1 looking in the direction indicated by the arrows.

Figure 3 is a horizontal sectional view taken substantially on the line 3—3 of Figure 1 looking in the direction indicated by the arrows.

The device comprises a rectangular plate,

turned in a rearward direction as indicated by the numeral 2 so as to reinforce the said plate and the plate is provided near its upper edge with an opening 3 for the passage of a securing screw or the like indicated by the numeral 4 whereby the plate may be secured to and suspended upon a door or door frame or other fixed support. The device is, as stated above, intended, primarily for indicating to an ice-man, the number of pounds of ice to be delivered and it may likewise be employed to indicate the number of loaves of bread to be delivered or in fact the quantity of any commodity, and there is printed or otherwise depicted upon the face of the plate a word, indicated by the numeral 5, indicating the nature of the commodity, and below this word the plate is stamped to provide a plurality of suspension hooks indicated by the numeral 6.

The ordinal-bearing plates above referred to are indicated by the numeral 7 and each of these plates is of oblong rectangular form and has its upper marginal portion overturned as indicated by the numeral 8 so as to be reinforced and each plate bears a printed or painted ordinal 9 and an opening 10 is formed in each of the plates 7 below the overturned marginal portion 8 thereof so as to adapt each plate to be supported upon one of the hooks 6.

Ordinarily ten of these plates will be employed in connection with each of the devices and the plates will be numbered from 1 to 0 so that any desired combination of two or three ordinals may be effected in order to indicate the number of pounds of ice or the number of articles to be delivered. In order that the plates may be securely held in place in their suspended and assembled relation, as shown in Figure 1, a strip 11 of sheet metal is riveted along its lower marginal portion as at 12 to the face of the plate 1 so that the strip extends transversely of the plate below the hooks 6 and the ends of the strip are overturned in a rearward direction as indicated by the numeral 13 so as to be anchored to and embrace the side edges of the plate 1. The upper portion of the strip is sprung in a forward direction so that the lower marginal

portions of the ordinal-bearing plate 7 may be engaged between the face of the plate 1 and the upper portion of the strip 11 and, if desired, the upper marginal portion of the strip may be overturned in a rearward direction as indicated by the numeral 14.

In order that a plurality of the ordinal-bearing plates may be stored in convenient position for use, a pocket indicated in general by the numeral 15, is provided, and this pocket is preferably formed integral with the lower portion of the plate 1 and is bent so as to provide a front portion 16, end walls 17, and laterally extending flanges 18 at the rear edges of the end walls, these flanges being riveted or otherwise secured as at 19 to the plate 1, at the juncture of the portion of the plate from which the pocket is formed, with the plate 1, the sheet blank is curved to form 20 a bottom 20 for the pocket.

A bolt 21 is secured through aligned openings in the upper marginal portion of the front wall 11 of the pocket 16 and through the plate 1, and a sleeve 22 is fitted onto this 25 bolt and, by reference to Figures 1 and 3 of the drawings, it will be observed that such of the ordinal-bearing plates as are not in use, may be arranged in groups in the pocket, at opposite sides of the bolt 21.

30 What I claim is:—

1. A device of the class described comprising a plate bearing, upon its face, the name of a commodity, suspension hooks upon the plate below the said name, ordinal-bearing plates removably suspended from the hooks, and a strip secured to the face of the first mentioned plate and spaced at its upper edge therefrom to receive and retain the lower edges of the suspended ordinal-bearing 35 plates.

2. A device of the class described comprising a plate bearing, upon its face, the name of a commodity, suspension hooks upon the plate below the said name, ordinal-bearing plates removably suspended from the hooks, a pocket upon the first mentioned plate to accommodate a plurality of the ordinal-bearing plates, and a bolt secured through the first mentioned plate and the 45 wall of the pocket between the ends of the pocket to brace the same and also serve as a means for spacing separate groups of the ordinal-bearing plates.

In testimony whereof I affix my signature.

50 WILLIAM HENRY SANDEFUR.
